UNITED STATES PATENT OFFICE.

HARRY W. LEAVITT, OF TUSCOLA, ILLINOIS.

LAWN-MOWER.

SPECIFICATION forming part of Letters Patent No. 760,695, dated May 24, 1904.

Application filed January 10, 1903. Serial No. 138,532. (No model.)

To all whom it may concern:

Be it known that I, HARRY W. LEAVITT, a citizen of the United States, residing at Tuscola, in the county of Douglas and State of Illinois, have invented certain new and useful Improvements in Lawn-Mowers; and I do hereby declare the following to be a full, clear, and exact description of the invention, such as will enable others skilled in the art to which it applies to make and use the same.

My invention has relation to mowing-machines, and more particularly to lawn-mowers designed to be operated by hand-power, though it is obvious that other forms of motive force may be adopted in some instances with advantage.

The object of my invention, among others, is to provide an attachment for a lawn-mower of the usual or any preferred construction whereby the momentum of the machine when in operation will be greatly conserved and augmented at the expense of a minimum amount of mechanism.

A further object, among others, is to provide a simple clutch mechanism which will prove reliably efficient in the performance of its office, whereby the sickle will be positively driven when the machine is moved forward and will be permitted to remain idle when the movement of the machine proper is reversed.

Other objects and advantages will be hereinafter clearly set forth, reference being had to the accompanying drawings, which are made a part of this application, and in which—

Figure 1 shows a perspective view of my invention complete ready for use. Fig. 2 shows a rear elevation of my invention illustrated in Fig. 1 with the handle removed. Fig. 3 is a sectional view of my machine, taken on line $\alpha\alpha$ of Fig. 2 and showing the parts on a slightly-enlarged scale. Fig. 4 is a detail view of my improved clutch mechanism and contiguous parts on a substantially normal scale, while Fig. 5 shows the clutch mechanism and shaft illustrated in Fig. 4 separated from each other and ready to be assembled each in its respective place. Fig. 6 is a plan view showing some of the elements in section. Fig. 7 is a side view of the standard 11 removed looking in the direction of the collar 6.

In order to conveniently refer to the details of my invention and coöperating accessories, numerals will be employed, the same numeral referring to a similar part throughout the several views.

Referring to the numerals on the drawings, 1 indicates the driving or traction wheels of my lawn-mower, while 2 designates the tongue or handle thereof, which is constructed substantially in the usual manner and is provided with a bifurcated lower end, the branches 3 of which are adapted to take over suitable lugs provided on a contiguous part of the frame. An axle 4 is provided and which is loosely mounted in journals 5, which are extended through the seats or collars 6 and 6', said journals being held against rotation therein by the set-screws 7. The extensions 5 are eccentrically disposed upon the shaft 4, thereby permitting a proper adjustment of the shaft 4 by means of said set-screw, whereby certain parts carried by the shaft 4 may be relatively disposed. The inner end of the shaft 4 and its collar 6 are supported by the standard 11, soon to be described.

It will be observed that the other collar-section, 6', constitutes an integral part of the stationary head—that seen at the right in Fig. 6 there being one of said heads for each of the traction-wheels, said heads being secured together by the cross-bar 9, bolted in engagement with the head, as indicated by the bolts 10. It is obvious that said cross-bar 9 affords a bearing or support upon which is erected the standard 11, as more clearly shown in Fig. 2, said standard having the inwardly-directed arm 12, in the free end of which is provided a suitable bearing for the vertical shaft 13, the lower end of said shaft being seated in suitable bearings in the bar 9.

The lower end of the shaft 13 extends entirely through a suitable aperture provided in the bar 9 and is provided upon its under side with the head or disk 14, having a wrist-pin 15, designed to connect with the pitman 16, the outer end of which is operatively connected to the driving-bar 17, pivoted upon the bracket 18, carried by the forwardly-projecting arm 19, the pivot-point being indicated by the numeral 20.

The arm 19 is supplemented by the arm or frame section 21, said parts being adjustably supported by the auxiliary carrying-wheels 22 and are designed to carry the sickle 23 and the bar coöperating therewith. The disk or head 14 and the shaft 13 are driven by means of a train of gearing consisting in this instance of a master or driving gear 24, secured to the shaft 25, which latter is supported in suitable bearings 26, operatively disposed in the collars or seats 27 and held against rotation in said seats by the set-screws 28.

The shaft 25 is eccentrically disposed with respect to the bearings 26, whereby a proper adjustment of said bearing may be secured by the set-screw 28, which latter is carried by the extension or seat 27, as clearly shown in Fig. 4. The extension or seat 27 also provides a housing for the clutch mechanism employed to coöperate with the shaft 25 and comprising the member 29, which is provided upon its inner face with a pair of oppositely-inclined recesses 30, designed to engage a pin 31, whereby the member 29 is held against reverse rotation upon its shaft. The opposite face or outer side of the member 29 is provided with inwardly-directed tapering recesses which terminate in the shoulders 32, and designed to coöperate with said shoulders 33 are the extensions 33, formed upon the inner face of the gear 34, which latter is rotatably disposed upon the shaft 25 and held thereon by the key 35 or the equivalent thereof.

The gear 34 is designed to engage with and be driven by a plurality of inwardly-directed cogs 36, carried by the traction-wheels 1, as is common. By means of the clutch mechanism just described, it is obvious that when the lawn-mower is driven forward the shaft 23 will be positively rotated to operate the driving-gear 24; but when the machine is moved backward the inclined faces of the teeth 33 will ride upon the inclined faces of the recesses which terminate in the shoulders 32, and the result will be that the member 29 will be forced inward against the pins 31 sufficiently to permit the teeth 33 to pass said member. When, however, the machine is again driven forward, the teeth 33 will engage the shoulders on the recesses 30 and cause the beveled faces upon the opposite side of said member to ride against the pins 31, thereby insuring that said member 29 will be moved outward by reason of said pins, and thereby frictionally lock the gear 34 and the shaft 25 in union with each other.

I am thus enabled to entirely dispense with spring mechanism for holding the detent or clutch mechanism in engagement with each other, inasmuch as a wedge-like action is set up between the member 29 and the gear 34, owing to the construction of said parts and by reason of the location of the pin 31. The driving-gear 24 meshes with a spur wheel or gear 24^a, forming an integral part of the bevel

gear 37, which latter is rigidly keyed to its supporting-shaft 4 and is designed to mesh with and drive the beveled gear 38, which latter is rigidly keyed to the shaft 13.

I desire to call special attention to the balance-wheel 39, rigidly secured to the upper end of the shaft 13, as it is by means of said wheel that I am enabled to preserve the force or momentum of the machine to a sufficient extent to insure that the sickle will be positively driven forward at least momentarily even after the machine itself has come to a full stop, thereby guarding against the sickle becoming choked. By means of the mechanism herein described and illustrated it will be seen that the simple train of gearing which I have provided for communicating motion to the sickle may be actuated at the expense of a minimum amount of power and that the machine may be readily reversed and moved rearward without fear of stopping and choking the sickle, inasmuch as the momentum of the train of gears will be preserved and maintained to the extent of clearing the sickle of choking material.

The simple form of clutch mechanism will admit of the machine being moved backward without danger of breaking any of the parts or disengaging the spring tension usually employed to control the clutch.

It will be understood that my improved mower may be any preferred size and made of any material deemed most suitable for the purpose and that the several parts thereof being interchangeable may be very cheaply manufactured and readily assembled each in its respective operative position.

While I have described the preferred construction and combination of parts deemed necessary in materializing my ideas and applying my invention to practical use, I wish to comprehend in this application all possible substitutes and equivalents which may be considered as fairly falling within the scope of my invention.

Believing that the advantages and manner of using my improved lawn-mower have thus been made clearly apparent, further description is deemed unnecessary.

What I claim as new, and desire to secure by Letters Patent, is—

1. In a lawn-mower of the class described, the combination of a frame, carrying-wheels therefor, two parallel shafts having eccentric journals, collar-sections through which said journals are extended, a connection between the carrying-wheel and one of said shafts, stationary heads integral with said collar-sections, means connecting said heads together, a standard supported on said connecting means, an inwardly-directed arm on said standard, a vertical shaft, the free end of which has a bearing in said arm and the lower end having a bearing in said connecting means, a disk with wrist-pin connected with the lower

end of said vertical shaft, a pitman connected with the said wrist-pin, an operative connection between the pitman and the sickle-bar, and an operative connection between said vertical shaft and one of the first-mentioned parallel shafts.

2. In a lawn-mower of the class described, the combination of a frame, carrying-wheels therefor, two parallel shafts having eccentric journals, a connection between one of said shafts and the carrying-wheels, collar-sections through which said journals are extended, means including said eccentric journals and collar-sections for adjusting said shafts, stationary heads integral with said collar-sections, means connecting said heads together, a standard supported on said connecting

means, an inwardly-directed arm on said standard, a vertical shaft, the free end of which has a bearing in said arm and the lower end having a bearing in said connecting means, a disk with wrist-pin connected with the lower end of said vertical shaft, a pitman connected with the said wrist-pin, an operative connection between the pitman and the sickle-bar, a train of gearing, connecting the said vertical shaft and one of the said parallel shafts.

In testimony whereof I affix my signature in presence of two witnesses.

HARRY W. LEAVITT.
